UNITED STATES PATENT OFFICE.

HARRY BRANDLEY, OF MATFIELD GREEN, KANSAS.

DOOR-LATCH.

1,035,077.

Specification of Letters Patent.

Patented Aug. 6, 1912.

Application filed May 20, 1912. Serial No. 698,534.

To all whom it may concern:

Be it known that I, HARRY BRANDLEY, a citizen of the United States, residing at Matfield Green, in the county of Chase and State of Kansas, have invented certain new and useful Improvements in Door-Latches, of which the following is a specification.

The present invention appertains to latches of the type especially adapted for 10 use in connection with barn doors, gates, or similar structures.

A latch embodying the invention is composed primarily of a suitable spindle mounted on the door jamb and provided with operating arms upon opposite ends, one arm being arranged on the inside of the door and the other on the outside of said door when the latter is closed. The operating arms above referred to constitute handles 20 for manipulating the spindle to latch and unlatch the door, and one of said arms performs a locking function by coöperation with a peculiarly arranged hasp, the last mentioned parts being adapted to be locked 25 together with a pad-lock, or the like when it is desired to lock the door against unauthorized access to the structure upon which it is arranged.

For a full understanding of the present 30 invention, reference is to be had to the following description and to the accompanying drawings, in which—

Figure 1 is a front elevation of a structure including a door, and illustrating the invention as applied thereto, the parts being partly broken away. Fig. 2 is a sectional view taken on the line 2—2 of Fig. 1. Fig. 3 is a transverse section taken about on the line 3—3 of Fig. 2 and looking downwardly.

Throughout the following detail description and on the several figures of the drawings, similar parts are referred to by like reference characters.

In all of the views of the drawings, the 45 latch is shown in a position in which it holds the door closed and locked by means of a pad-lock, dotted lines in Fig. 3 showing the movement of the locking arm in order to permit free opening movement of 50 the door.

Specifically describing the invention in connection with the drawings, 1 denotes a structure such as a barn or equivalent means, the door 2 being hingedly mounted thereon, 55 as shown at 3 and adapted to swing into closed and open positions, in the former of

which positions, the door coöperates with the usual jamb 1'. A supporting plate 4 is fastened by screws or other fastenings to the jamb 1' and is provided with a bearing 4' to 60 receive the spindle 5 of the latch means. The spindle 5 is horizontally arranged in the bearing 4' and is provided at its inner end with a downwardly extending arm constituting a handle 6, which handle also performs the function of a stop, as will be pointed out more fully hereinafter. A locking arm 7 is carried by the outer end of the spindle 5 and terminates at its free extremity in a lateral stop 8 and an extension 65 70 9 formed with an opening therethrough. Attached to the outer side of the door 2 is a plate 10 formed with an arc-shaped guide 11 comprised by a flange of the plate 10. A hasp 12 is pivoted at one end to the lower 75 80 extremity of the plate 10 and is formed with an opening adapted to register with the opening in the extension 9 of the locking arm 7, as clearly shown in Fig. 3 of the drawings.

In the practical use of the invention, to hold the door 2 closed, the parts will be arranged, as shown in full lines in the several figures of the drawings, the inner handle or arm 6 being pendent and resting close 85 against the jamb 1' out of the way, while the locking arm 7 is arranged transversely of the door, with the stop 8 resting on the pivotally connected portion of the plate 10 and hasp 12. The arm 7, of course, prevents 90 opening movement of the door according to the above arrangement and if it is desired to permanently lock the door, a pad-lock, such as shown at 13, is engaged with the parts 9 and 12, the latter being raised to a 95 horizontal position for this purpose. To unlatch the door, the operator has only to grasp the extension 9 and move the same to the dotted line position shown in Fig. 3. The spindle 5 makes a half revolution in the 100 above operation and the arm 7 is held in the dotted line position aforesaid by the engagement of the handle 6 with the jamb, said handle under these conditions projecting upwardly or vertically from the spindle. 105 When a lock, such as a pad-lock is not employed, the latch means described will perform the function of a latch solely and the locking arm 7 is susceptible of operation from the outside of the door as well as from the interior of the structure upon which the door is mounted. The hasp 12 when not in

use for locking purposes will normally rest in a vertical position against the outside of the door, as illustrated by dotted lines in Fig. 2.

5 Intermediate its ends, the spindle 5 is formed with a boss 14 passing through a slot in the bearing 4' and preventing longitudinal movement of the spindle in said bearing.

10 Latch means, as above set forth, are very simple in construction and afford practical advantages of obvious import. It will be understood that while the parts 6 and 7 are illustrated as integral with the spindle 5 in the drawings, they may be detachably secured thereto in any positive and effective manner desirable.

Having thus described the invention, what is claimed as new is:

20 1. In combination with a door and structure upon which said door is mounted, the latter including a suitable jamb for the door, latch means consisting of a spindle mounted on the jamb, a locking arm at one end of said spindle adapted to engage with the door to hold the latter closed, an arm at the other end portion of the spindle providing a handle for manipulation of the spindle from the inside of the door, a hasp mounted on the door, and means to connect said hasp and locking arm for preventing unauthorized manipulation of the hasp.

25 2. In combination with a door and structure upon which said door is mounted, the latter including a suitable jamb for the door, latch means consisting of a spindle mounted on the jamb, a locking arm at one end of said spindle adapted to engage with the door to hold the latter closed, a hasp pivotally mounted on the door, and means to connect said hasp and locking arm.

30 3. In combination with a door and structure upon which said door is mounted, the

latter including a suitable jamb for the door, 45 latch means consisting of a spindle mounted on the jamb, a locking arm at one end of said spindle adapted to engage with the door to hold the latter closed, a stop projecting from the locking arm, and a plate secured to the door and having a guide to coact with 50 said stop.

4. In combination with a door and structure upon which said door is mounted, the latter including a suitable jamb for the door, 55 latch means consisting of a spindle mounted on the jamb, a locking arm at one end of said spindle adapted to engage with the door to hold the latter closed, a stop projecting from the locking arm, a plate secured to the door and having a guide to coact with 60 said stop, a hasp pivoted to said plate, and means to operatively connect the hasp with the locking arm.

5. In combination with a door and structure upon which said door is mounted, the 65 latter including a suitable jamb for the door, latch means consisting of a spindle mounted on the jamb, a locking arm at one end of said spindle adapted to engage with the door to hold the latter closed, a stop projecting 70 from the locking arm, a plate secured to the door and having a guide to coact with said stop, a hasp pivotally connected to said plate and movable to occupy positions close 75 against the door or extending outwardly from the door beneath the locking arm, said locking arm and hasp having registering openings, and a device engaging said openings to connect the hasp and locking arm 80 against unauthorized operation.

In testimony whereof I affix my signature in presence of two witnesses.

HARRY BRANDLEY.
